UNITED STATES PATENT OFFICE.

JOHN H. HELMS, OF FORTVILLE, INDIANA.

CLAMP.

Application filed July 9, 1927. Serial No. 204,576.

This invention relates to clamping devices and pertains particularly to a piston clamp designed primarily for use in connection with pistons or valves of a railway air brake.

5 The primary object of this invention is to provide, in a manner as hereinafter set forth, an improved type of clamp, designed to be inserted in a portion of the piston for the purpose of securely maintaining a number 10 of readily separable parts in assembled relation so that the same may be removed from the piston cylinder as a unit.

Another object of the invention is to provide, in a manner as hereinafter set forth, 15 a clamping device which can be readily operated to grip the inner walls of a cylinder to secure a firm hold upon the same so that the element may be removed from its cylinder housing.

20 Numerous other objects and advantages of the present invention will become apparent as the description of the same proceeds and the invention will be best understood from a consideration of the following detailed description taken in connection with the accompanying drawing forming a part 25 of this specification, with the understanding, however, that the invention is not confined to any strict conformity with the showing 30 of the drawing but may be changed or modified so long as such changes or modifications mark no material departure from the salient features of the invention as expressed in the appended claims.

35 In the drawings:

Figure 1 shows a usual form of piston such as is used in railway air brakes showing the same in longitudinal section and showing the device embodying the present

40 invention applied thereto,

Figure 2 shows the device embodying this invention, removed from engagement with the work,

Figure 3 is a transverse section taken 45 upon the line 3—3 of Figure 1, and

Figure 4 is a section taken transversely of Figure 1 upon the line 4—4.

Referring now to the drawing in detail wherein like numerals of reference indicate 50 corresponding parts throughout the several views, the numeral 1 indicates the usual type of piston having formed integral therewith the relatively long hollow sleeve 2 over which is slidably fitted a compression spring

55 3 which is held in position thereon by the head plate 4, the head plate being provided

with central apertures to receive the outer end of the cylinder 2. This outer end of the cylinder is open as is clearly shown in Figure 1.

60 Considerable difficulty is encountered in removing pistons of this character from their cylinders as the head plate 4 slides over the sleeve 2 and can be readily forced therefrom under the pressure of the spring 65 3 thus permitting the parts to readily separate.

In order to overcome this objectionable feature and to hold a piston, spring and head 70 in assembled position, when removed from the cylinder in which the piston operates a clamping member is provided consisting of a relatively long shaft indicated as a whole by the numeral 5 which shaft comprises a short outer portion 6 and a relatively long portion 7 provided throughout its length with screw threads. This portion 7 is of materially less diameter than the portion 6 and extends through an aperture 8 formed centrally through a circular plate 9 which plate 75 is provided with the peripheral flange 10. The plate 9 abuts the shoulder 10 formed at the point of union between the sections 6 and 7 and is thus limited in its movement upon the threaded shaft 7. The outer end of the shaft section 6 is provided with the hand wheel 11, the utility of which will become 80 apparent as the description proceeds.

85 The inner face of the head 9 at diametrically opposite points on either side of the opening 8 is provided with the ears 12 and from each of these ears a relatively long arm 13 extends, the free inner end of which arms terminate in the jaws 14, the outer surface of which are convexed and provided 90 with transverse ridges or teeth 15. As is clearly shown in Figure 4 these jaws 14 are materially broader than the arms 13 and the outer faces thereof are of a curvature to conform to the curvature of the cylinder 2. 100

95 The free ends of the arms 13 beneath the jaws 14 are rounded as at 16 and slidably engage in the tapered groove 17 formed longitudinally of the surface of the nut member 18, which nut is provided with a central 105 longitudinally extended bore 19 which is provided with threads for the reception of the threaded shaft 7 which is designed to extend therethrough as is shown in Figure 1.

110 The arms 13 inwardly of the jaw ends each has the transversely extending pin 20

passed therethrough and projecting from the opposite faces thereof and each end of the pin of one arm is connected with the adjacent end of the pin of the other arm by the spring 21. These springs located on opposite sides of the screw 7, act to draw the arms 13 together thus causing the same to grip the nut 18 tightly between their outer ends.

10 In operation, the arms 13 of the device are extended into the free open end of the cylinder 2 until the plate 9 engages the free end of the cylinder and the flange 10 surrounds the same. The wheel 11 is then rotated in the proper direction to cause the nut 18 to be drawn toward the wheel upon the threaded shaft or screw 7 thereby forcing apart the free ends of the arms 13 to cause the serrated faces of the jaws 14 to engage the inner surface of the wall of the cylinder. It will be readily understood that by this operation the spread jaws can be caused to tightly grip the cylinder and the flange 10 of the head plate 9 will then prevent the plate 4 from being forced off of the cylinder 2 by the spring 3 and the three elements can be removed as a unit from the piston cylinder.

What I claim is:

30 1. A clamp of the character described, comprising a threaded shaft, a plate traversed by said shaft and rotatable thereabout, a nut member threaded upon and

movable longitudinally of said shaft and having longitudinally extending grooves 35 formed in the face thereof, and a pair of jaw carrying arms normally arranged longitudinally of said shaft and having pivotal connection at one end with said plate the other end of each arm being slidable in a 40 groove of said nut member.

2. A cylinder engaging clamp of the character described, comprising a relatively long shaft having screw threads formed throughout substantially half the length 45 thereof, a plate member traversed by and rotatable about said shaft and having a flange formed about the edge thereof for engagement over the end of a cylinder, a pair of arms arranged longitudinally of the 50 threaded portion of said shaft, means for pivotally securing said arms at one end to said plate, a nut member threaded upon said shaft engaging the free end thereof and having the peripheral surface provided 55 with a pair of tapered grooves, designed to receive the free ends of said arms, jaw members formed upon the free ends of said arms for engagement with the inner face of a cylinder, and resilient members connecting 60 said arms and normally tending to draw the same together, substantially as and for the purpose described.

In testimony whereof I affix my signature.

JOHN H. HELMS.
